ITEM CHECKING DEVICE

Abraham D. Olson, Osborn, Ohio, and
Isaac A. Morris, Clifton Springs, N. Y.

Application January 2, 1947, Serial No. 719,646

6 Claims. (Cl. 116—128)

(Granted under the act of March 3, 1883, as
amended April 30, 1928; 370 O. G. 757)

1

The invention described herein may be manufactured and used by or for the Government for governmental purposes without payment to us of any royalty thereon.

This invention relates to a device which is more particularly adapted for use in connection with army aircraft, for supporting a check list and for indicating the items enumerated on said list which have already been attended to or accomplished and which items remain non-accomplished.

At the present time all army aircraft are required to have check lists placed at all important crew stations, such as the pilot, co-pilot and engineer. These so-called check lists, as their name implies, are simply a piece of paper or a card having thereon listed the items that are to be checked and being hung adjacent to the station for which intended.

Such a check list system as formerly in use is unsatisfactory for several reasons:

(a) Crew members do not follow the lists because each man uses his own sequence in checking the various items and the lists are not adaptable to each individual system, thus resulting in crew members skipping some items as they proceed in their check and then forgetting to come back and accomplish the same.

(b) Check lists are usually hung up in the airplane, sometimes insecurely, and thus they become detached and lost.

(c) Check lists, rather than containing items which involve the safety and efficiency of the airplane, have actually become short guides on the manner of flying the airplane, and have therefore lost their importance.

It is an essential object of our present invention to provide a novel device for securely supporting a check list and for readily checking the items enumerated on said list, which device is especially adapted for use in conjunction with aircraft, whereby one can easily and quickly check or indicate each item involved as having been attended to or accomplished, just as soon as that is done, and show that clearly, in order to avoid any chance of skipping any one of such items.

Another object of this invention is to provide such a checking device arranged for use in an airplane, which device is readily operable and whereby the mechanism that indicates which of the items are accomplished and which are not accomplished is at all times clearly shown, so as to provide a clear visual picture of what has already been done and what is yet to be done.

These and various other objects and advantages

are attained with this invention, as will become apparent from the following description, taken in connection with the accompanying drawing wherein the invention is shown in its preferred form, it being evident that other arrangements and forms of construction may be resorted to for carrying out the objects and purposes of this invention.

In the drawing:

Fig. 1 is a plan view showing the item checking device in a preferred form of construction.

Fig. 2 is a cross sectional view thereof, taken substantially on line 2—2 of Fig. 1.

Fig. 3 is an enlarged sectional view of the lever construction.

Fig. 4 is a fragmentary view of this device showing the registering openings which form the pocket for retaining the lever in its tilted position.

This novel item checking device is arranged substantially in the form of a check list board which comprises a support 11 and a set of levers 12 that are tiltably mounted thereon by means that functions with a snap-action, so as to be readily operable and at the same time to be held firmly in position, in order to adapt this device particularly for use in checking the requisite items in preparation for an airplane flight.

This support 11 is preferably built up from a back panel or cover 13 and a front panel or cover 14 which have spacing strips mounted therebetween, said strips including a pair of spacing bars 15 and 16 between the two opposite side parts of the panels and also on end strip 17 placed between the lower ends of the panels and the plates. This provides a pocket or recess 18 between the two panels and the three strips, said pocket being open at the upper end, opposite said end strip 17, adapted to receive and hold therein a check list 19 which bears on its spaced lines 20 the set of items that are to be checked. A pair of plates 21 and 22 are mounted on the two opposite side parts of the front panel 14, above the bars or strips 15 and 16, respectively, and these panels and plates and strips are secured firmly together, by rivets 23 or other suitable means.

The back panel 13 and the plates 21 and 22 positioned upon the front panel are preferably of metal, while said front panel 14 is of transparent material, as Plexiglas or glass, so that the items enumerated on the check list 19, located in the recess 18 behind said transparent panel 14, can be readily seen. The strips 15, 16, and

17 are of light material suitable for this spacing purpose, such as cardboard for example.

A series of pockets 24 are provided on the support 11 for mounting the levers 12 therein to be tiltable laterally of the board, each lever being adjacent to and in line with one of the items set forth on a line 29 on said check list 19, as best shown in Fig. 1. These pockets are preferably provided by constructing a set or series of oblong apertures 25 elongated laterally of the plate 21, also a long slot 26 extending longitudinally along the side part of panel 14 and located beneath said apertures, and a set of rectangular apertures or openings 27 provided in bar 15, being positioned beneath and registering with said slot 26 and said aperture 25, whereby the back panel 13 forms the bottom of each pocket 24, as best seen in Fig. 2. The aperture 25 is smaller than the opening 27 or the slot 26, thus providing a restricted aperture or outlet on the pocket.

The lever 12 preferably consists of a stem or shank 28 which has holding means 29 on its inner end, preferably in the form of an annular boss or shoulder, said shoulder being positioned in the pocket 24 and being larger than the aperture 25, to prevent removal of the lever, while the stem 28 extends through and above said aperture and is tiltable laterally therein. A plunger 31 is slidably mounted in a bore 32 in the stem 28 and has its outward end protruding below the stem, and a spring 33 in said bore presses on the stem and constantly urges it resiliently outwardly to bear against the pocket wall. Holes 34 are provided in the support for receiving bolts or the like to hang up this check list board in the appropriate place in the airplane.

Our disclosed construction and arrangement of the support and of the levers furnishes each lever with a snap-action wherein the spring-pressed plunger 31 aided by the retaining shoulder 29 on the stem, serves to press the plunger against the back panel at the bottom of the pocket, while the shoulder bears against the top and the bottom walls of the pocket, thereby holding the lever firmly in its set position, tilted either toward the right-hand side of the support and toward the particular item set forth on the list, to show that the item has been accomplished, or similarly tilted away from the item, to show that it is non-accomplished and still awaits attention. This lever is at the same time quickly and easily actuated by the mere motion and pressure of a finger thereon in the appropriate direction.

The check list board can be readily hung up in an airplane, and at first the levers are all tilted to their inactive position away from the items as the pilot starts preparing the ship for flight, and as he accomplishes certain actions which are enumerated on this list, the corresponding lever is easily actuated due to its snap-action to show that the item has been accomplished. This form of device with these levers thus provides a readily observable visual picture of what items are accomplished and what items are non-accomplished and still require attention.

We claim:

1. An item checking device comprising a supporting board including a rear panel and a transparent front panel, parallel spacing strips between said panels to space them apart and provide a recess therebetween for holding an item check list therein, one of said spacing strips having elongated parallel openings therein,

each opening in registering alignment with an item on the check list, a cover panel in front of the last mentioned spacing strip having elongated parallel apertures therein which are shorter and narrower than the elongated openings in the spacing strip and in centralized registration with the strip openings to provide a series of elongated parallel item checking lever receiving pockets with restricted outlets, a series of item checking levers, each freely disposed in one of the pockets and having a stem handle projecting through the restricted outlet of the pocket and a stop-shoulder adjacent its inner end inside of the pocket and bearing against the back of said cover panel to retain the checking lever rockable in the pocket, spring pressed plunger detent means projecting from the inner ends of the checking levers toward the bottoms of the pockets to resiliently and slidably engage the same, yieldably retaining the checking levers in tilted position with their stem portions pointed either toward or away from the check list items.

2. Apparatus as claimed in claim 1, in which the stop-shoulder surrounds the end of the checking lever and inclines outwardly and downwardly toward the inner end of the checking lever.

3. Apparatus as claimed in claim 2 in which the detent means includes a cylindrical guide bore extending into the inner end of the checking lever toward the stem handle and the plunger, is cylindrical and slidably guided in the guide bore with a tapered extremity engaging the bottom of the recess and includes a coil spring within the bore engaging the plunger to yieldably force the plunger outwardly engaging the tapered extremity against the bottom of the recess, and to engage the incline surrounding shoulder of the checking lever against the cover panel at the periphery of the elongated opening therein which forms the restricted opening to the pocket.

4. In an indicating device of the class described, a back panel, an elongated spacing strip extending across the front face of the back panel, said elongated spacing strip having a plurality of transverse parallel elongated openings extending therethrough to the back panel to form elongated parallel pockets with the back panel having parallel side walls, a front cover panel covering the spacing strip having a plurality of transverse, spaced, parallel elongated openings therethrough of shorter and narrower dimensions than the transverse openings in the spacing strip and disposed in centralized registration with the spacing strip openings, indicating levers rockably disposed in the openings having handles projecting outwardly therefrom through the front panel openings, each indicating lever having a width in the front panel opening slightly less than the width of this opening and a width within the pocket greater than the front panel opening and formed with a longitudinal guide bore extending into its inner end and opening toward the back panel, a plunger slidably in the guide bore having a tapered extremity facing and engaging the back panel, and spring means in the bore of the lever yieldably urging the plunger outwardly against the back panel at the bottom of the pocket.

5. In an indicating device of the class described, an indicating board having a back panel, an elongated front cover panel extending along the front face of the back panel adjacent one edge thereof, spacing strip means between the front and back panels spacing the panels in parallel relation, said front panel and said spacing strip

means having a plurality of spaced parallel elongated openings formed therein to form recesses, each recess having an elongated restricted outlet opening through the front panel and a larger registering opening in the spacing strip means behind the front panel with parallel side walls, an indicating lever freely positioned and rockable in each recess, having a cylindrical stem portion extending through the restricted opening and beyond the front panel to form a handle, and an inner portion within the recess having an annular incline stop flange surrounding the lever between the restricted opening and the bottom of the recess to restrict outward movement of the lever through the restricted opening, said inner portion inclining outwardly toward the bottom of the recess and formed with a guide bore extending inwardly away from the bottom of the recess, a plunger slidable in said guide bore having a tapered outer extremity for engagement with the bottom of the recess, and spring means in said guide bore engaging the plunger to yieldably force the same outwardly against the bottom of the recess.

6. In an item checking device of the class described, a back panel having means thereon for supporting a list of items to be checked, a front cover panel, an elongated spacing strip means extending along the front of the back panel adjacent one edge thereof to space the front panel from the back panel, said front panel and spacing strip having elongated parallel registering openings formed therein each extending in alignment with an item on the aforesaid item list, the said elongated parallel openings in the front panel being shorter and narrower than the registering elongated openings in the spacing strip means,

and the openings in the spacing strip means extending therethrough from the front panel to the back panel and having parallel side walls perpendicular to the back panel, an indicating lever freely positioned and rockable in each of said registering openings having an annular surrounding shoulder between the front panel openings and the base panel and an outer cylindrical handle stem portion projecting through the front panel openings with a diameter slightly less than the width of the elongated front panel openings and an inner end portion facing the back panel and terminating in spaced relation to the back panel, said inner end portion being formed with a guide passage therein, a plunger slidable in said guide passage having an outer tapered camming extremity engaging the back panel, and spring means within said guide passage engaging the plunger, forcing the same outwardly against the back panel, to yieldably retain the indicating levers tilted in the openings in the front panel and said spacing strip means.
